OHIO BRASS COMPANY, OF MANSFIELD, OHIO, A CORPORATION OF NEW JERSEY

CONDUCTOR SUPPORT

Application filed June 27, 1929. Serial No. 374,073.

Our invention relates to conductor supports and particularly supports for a trolley wire, and the process of producing the same.

The object of our invention is to provide a support or ear which may be built up from several parts into a unitary device, thereby permitting the various parts of the ear to be made from material particularly suited to that part, as, for instance, the lips or portion which grip the trolley wire may be made of rolled or drawn sheet material; the supporting portion may be made of cast or drop forged material, or it may be of rolled material with a separately formed supporting member secured thereto.

Our invention resides in the new and novel construction, combination and relation of the various parts herein described and shown in the accompanying drawing and in the steps covering the process of producing the same.

In the drawing:—

Fig. 1 is a side view of one form of our invention with a portion in section.

Fig. 2 is an end view of Fig. 1.

Fig. 3 is a plan view of the lip portion of our invention as formed from sheet material.

Fig. 4 shows the method of uniting the lip portion and supporting web portion.

Fig. 5 shows another form of supporting portion formed of two separable parts, a web portion and a boss portion.

Fig. 6 is an end view of Fig. 5.

Fig. 7 is a sectional view of Fig. 4 taken on the line 7—7.

In the preferred embodiment of our invention we provide a lip portion 1 formed of sheet material, as in Fig. 3, and composed of any material desired such as hard or soft rolled or drawn copper, brass, bronze, aluminum or a ferrous metal, and is provided with slots or cut away portions 2. The lip portion 1 is formed into a U-shaped member of such size as to receive and fit the trolley conductor, after which the lips may be formed about the conductor by a workman installing the device.

In Figs. 1 and 5 are shown two forms of supporting members for the lip portion 1.

The form 3 shown in Fig. 1 is adapted to be made by a casting and comprises the web 4, the boss 5, which is usually internally threaded, and projecting lugs 6, better shown in Fig. 5. In Fig. 1 the boss 5 is integral, while in Fig. 5 the boss is separably formed, and in the latter case it is possible to form the web 4' from sheet material by means of stamping dies, and the material may be of a ferrous or non-ferrous material and the boss portion 5' may be of either a ferrous or non-ferrous character and secured to the web portion by means of rivets or screws 7 passing entirely through the parts.

It will be appreciated that our construction permits of a wide variation in the various materials from which the device is constructed, as, for instance, the portion 1 may be made of hard drawn copper and the portion 3 in Fig. 1 may be made of cast brass or bronze of any composition desired, or may be of a cast or forged ferrous material. In Fig. 5 the web 4' may be formed of sheet steel or any suitable non-ferrous material, while the boss portion 5' may be of a cast ferrous or non-ferrous material, or forged.

Referring to Fig. 5, the web 4' is formed as shown with the plurality of projecting lugs 6 adapted to be positioned within the recesses 2 of the lip portion, and the web 4 of Fig. 1 is provided with the same projecting lugs 6 to be received in the openings 2 of the lip portion, and these parts having been assembled, the parts are placed in an inverted position as shown in Fig. 4 and the projecting portions of the lugs 6 are then fused to form an integral alloy union with the adjacent portions of the lip portion 1 by means of an electrode 8.

The art of electric welding is extensively used at the present day and the various methods of arc welding are well known to those skilled in the art, as, for instance, the electrode 8 may be of either metal or carbon and if of metal, the end of the electrode will be fused and deposited upon the fused surface of the parts 1 and 4 or 4', and if the electrode 8 is of carbon, it will merely fuse the adjacent parts 1 and 4 or 4', and if additional

metal is required, it will be applied in the form of separate metal rods.

The parts may also be united by means of the oxyacetylene flame, also well known to those skilled in the art, but we find that the electric arc process is more desirable.

By making the openings 2 a little wider than the projecting lugs 6, the fused metal will flow downwardly through the space between the lugs 6 and the sides of the openings 2, and by placing a carbon mold on the outside of the parts at the point of weld and having a slight recess therein, this fused metal can be caused to form a fillet 9, which tends to brace the web and lip portion against a side strain.

In the form shown in Fig. 5, the lower faces 10 of the member 5' may be undercut so as to rest upon the upper portion of the lip portion 1 and thereby tend to brace the lip portion and web 4' against relative side movement.

It will be apparent that we have provided a built up support for a trolley wire of a plurality of parts united to each other and the method of forming such device and in which the use of a large range of materials is provided.

Having described our invention, we claim:

1. A conductor support comprising a U-shaped, grooved elongated member formed of sheet metal to receive the conductor and having lips bendable about the conductor to hold it on the U-member, a separably formed web member positioned exterior of the U-member and welded thereto and means to secure the web member to an overhead support.

2. A conductor support comprising a U-shaped, elongated member formed of sheet metal and having a groove to receive a conductor and having bendable lips to fold about the conductor, spaced openings through the U-member along the bight, a separably formed web member having projections spaced to correspond to the openings and extending into the openings when the web member is positioned, and the projections welded to the U-member to form a single unit and means to secure the web member to an overhead support.

3. A conductor support comprising a U-shaped, elongated member formed of sheet metal and having a groove to receive a conductor and having bendable lips to fold about the conductor, a web member, spaced projections on one member to enter intersections on the other member and the projections on the one member non-removably secured to the other member, and means to secure the web member to a support.

4. A conductor support comprising a U-shaped, elongated member formed of sheet metal and having a groove to receive a conductor and having bendable lips to fold about

the conductor, a web member, spaced projections on one member to enter intersections on the other member and the projections on the one member welded securely to the other member, and means to secure the web member to a support.

5. A conductor support comprising a plurality of separately formed parts, one part having a groove to receive a conductor and another part welded thereto and having means to support it and the first part.

6. A conductor support comprising a plurality of separately formed parts, one part having means for attachment to a support and another part to receive and hold a conductor, means on one part to interlock with means on the other part and the said parts welded together to form a unit construction.

7. A supporting device comprising a part to receive and hold a conductor, a separately formed device welded to the first part to support the same and a separately formed part secured to the second part and having means for attachment to a support to support the second said part.

8. A supporting device comprising a part to receive and hold a conductor, a separately formed part interlocked with the first part and the parts welded together, and separately formed means secured to the second part to secure the device to a support.

9. A supporting device comprising a part to receive and support a conductor, a separately formed part to support the first part and welded thereto against separation and a separately formed third part secured to the second part and having means to attach the second part to a support and other means to overhang the first part and engage the same to brace the first and second part against relative side movement.

10. A supporting device comprising a part formed of sheet copper having a groove to receive and hold a conductor, a separately formed part of dissimilar metal welded to the first part and having means to secure the parts to a support.

11. A supporting device comprising a part formed of sheet metal having a groove to receive and hold a conductor, a separately formed part of dissimilar metal interlocked with and welded to the first part and a separately formed part of metal dissimilar to that of the second part secured to the second part and having means to attach the parts to a support.

12. A supporting device comprising a part formed to receive and grip a conductor, a separately formed part to support the first part, the parts formed with cooperating intersections and projections and the projections on one part welded to the other part and separate metal fused to the external surface of the parts adjacent the projections and intersec-

tions to brace the parts and means to secure the parts to a support.

13. A supporting device comprising a part formed of copper base sheet metal and having a groove to receive and grip a conductor, a web portion formed of sheet metal and welded to the first part and a supporting member formed of a ferrous base metal secured to the web and having means to attach the parts to a support.

14. A supporting device comprising a part formed to receive and hold a conductor, a separately formed part welded to the first part to support the first part, a third supporting part secured to the second part and having a slot therein to receive the second member, transverse means to hold the second and third part together, means on the third part to engage the first part to brace the same and means to secure the third part to a support.

15. A trolley supporting device comprising a U-shaped part formed of sheet metal and having means to receive and hold a conductor and having the sides of the part for a distance back from the ends tapered both lengthwise and transversely to lessen the obstruction to a current collector when engaging and leaving the device, a part welded to the first part to support the same and having means to secure the device to a support.

16. The method of producing supports for conductors comprising the steps of forming up separate metal parts, one to engage and hold the conductor and the other to support the first part and then assembling the parts and welding the parts together, fusing together adjacent portions of each part and adding other fused metal thereto.

17. The method of producing supports for conductors comprising the steps of forming up separate metal parts, one to engage and hold the conductor and the other to support the first part, and then assembling the parts and welding the parts together, fusing together adjacent portions of each part.

In testimony whereof we affix our signatures.
